UNITED STATES PATENT OFFICE.

PAUL E. KELECOM, OF PARIS, FRANCE.

COTTER-PIN.

1,280,756.

Specification of Letters Patent. Patented Oct. 8, 1918.

Application filed January 5, 1918. Serial No. 210,549.

To all whom it may concern:

Be it known that I, PAUL E. KELECOM, a subject of the King of Belgium, and resident of Paris, France, have invented certain new and useful Improvements in Cotter-Pins, of which the following is a specification.

This invention is an improved cotter-pin adapted for use for the same general purpose as ordinary cotter-pins. The invention has for its object to simplify the construction, facilitate the insertion and removal of the pin, increase its resistance to shearing action while in use, and better adapt it for re-use after once having been used and extracted.

In the ordinary cotter-pin formed of two semi-cylindrical sections connected by a loop, the resistance operating at one time is usually only that offered by one of the two sections. The straightening of one section to facilitate the withdrawal of the pin is often interfered with by the juxtaposition of the other section and the loop does not present sufficient surface to permit the pin to be effectively gripped and pulled out. Much time is wasted in separating the ends of the sections of the ordinary pin when it is first inserted and time is also wasted in trying to get the two ends close together and parallel to facilitate the withdrawal. For this reason, workmen often omit cotter-pins where they should be used.

In my improved construction, the cotter-pin is formed essentially of three parts which may be, and preferably are, integral. The body of the pin is formed of a solid piece of wire of cylindrical or any other desired cross-sectional form and is of such length as to extend through the bolt, nut or other part to be held and leave a projecting end which may be bent over in any direction, as, for instance, by a light hammer blow. At the opposite end of the body there is formed an abutment or shoulder which is of such size, shape and position as to limit the extent to which the body portion may be inserted. Beyond this abutment, there is a further section of wire which may be, and preferably is, substantially straight and which provides means whereby the cotter-pin may be gripped between the fingers or with a pair of pliers to withdraw the cotter-pin or to hold it against rotation while the opposite end is being straightened.

By means of my improved construction, the resistance is greatly increased as the resistance of a solid wire is more than double the resistance of two semi-cylindrical sections of the same diameter. As only one section, namely the projecting end of the body, has to be straightened to withdraw the cotter-pin and as the cotter-pin may be effectively held against rotation during this straightening, a lesser number of cotter-pins are spoiled during withdrawal and the life of the cotter-pin is thereby materially increased. Even though the point is not straightened into absolute alinement with the body portion, yet the projection at the opposite end is of such size that the required amount of force may be exerted to pull out the pin. Ordinarily the point may be very easily brought to absolute alinement so that little force is required to effect the withdrawal. Due to the ease with which the point may be bent into or out of alinement and the pin inserted or withdrawn, a great deal of time is saved.

My invention may assume various different forms in each of which there are the three features hereinbefore referred to, namely the body portion, with its bendable point or end, the abutment for limiting the extent of insertion, and the projecting head or handle portion by means of which the pin may be withdrawn.

In the accompanying drawings, I have illustrated various different forms which my invention may assume.

In these drawings,

Figure 1 is an end view of a bolt and nut showing one form of cotter-pin;

Fig. 2 is a side elevation of the construction shown in Fig. 1, the bolted parts being in section;

Fig. 3 is a side elevation of the pin shown in Figs. 1 and 2, the abutment being an enlarged portion of the pin; and

Figs. 4 to 8 inclusive are side elevations of modified forms.

My improved cotter-pin may be employed for any of the ordinary purposes for which cotter-pins are used. In Figs. 1 and 2, I have shown merely as an example of such use a pair of plates 10 and 11 held together by a bolt 12 and castellated nut 13, the nut having transverse grooves 14 in its upper surface and the bolt having one or more transverse passages therethrough. The nut 11

may be tightened to such an extent that one of the grooves 14 is in alinement or in the same diametrical plane with the passage or one of the passages in the bolt, and the 5 cotter-pin may then be inserted to hold the nut against rotation. As will be understood, I do not claim anything new in this bolt and nut construction and have illustrated it merely as one construction in which my 10 cotter-pin may be employed.

In the specific form of cotter-pin shown in Figs. 1, 2 and 3, the body portion 15 is formed of a wire of circular or any other desired cross-sectional form and provided 15 intermediate of its ends with an abutment or shoulder 16 in the form of an enlarged portion of the wire. This enlarged portion may be readily formed by forcing one end portion endwise toward the other to shorten 20 the total length but increase the diameter at the desired point to form the abutment. At the opposite side of the abutment is the extension or head 17 which may be gripped to withdraw the cotter-pin. This may be 25 of any desired length although it should be of sufficient length to be easily gripped with the fingers or a pair of pliers and should not project out to such a distance as might cause it to form an objectionable extension. 30 The abutment 16 is of such size that it cannot pass through the opening receiving the body of the cotter-pin and the body of the pin is of such length that the end may be readily bent over after being extended 35 through the passage as shown in Fig. 1.

To form a more effective gripping head or end, the extremity of the projecting portion 17 may have a second shoulder, abutment, enlargement or offset portion 18, as shown 40 in Fig. 4, so that the pliers or other tool, or the fingers, may grip beneath it and be less liable to slip off if the portion is greasy.

In Fig. 5, I have shown the abutment 16^a in the form of a loop, the axis of which is 45 substantially at right angles to the general direction of the length of the pin; while in Fig. 7, I have shown the abutment as a loop 16^b with its axis substantially parallel to or in alinement with the pin.

50 In Fig. 6, I have shown an abutment or shoulder 16^c in the form of a U-shaped loop projecting laterally from the general direction of the pin, and have shown the head or grip portion 17 in alinement with 55 the body portion 15. The upper portion

of the loop 16^c may be shorter or longer, to bring the part 17 out of alinement or may be entirely omitted.

In Fig. 8, I have shown the abutment as a flattened portion 16^d, the flattening being produced in any suitable manner, as for instance by compressing, pounding or pinching the wire. It will of course be understood that the abutment may be formed in various other ways. 65

Having thus described my invention, what I claim as new and desire to secure by Letters Patent, is:

1. A cotter-pin consisting of a single piece of wire having its terminal portions substantially in alinement and of substantially the same cross-sectional size and form and provided with an abutment intermediate of its ends to limit the extent to which the cotter-pin may be inserted and to leave a 75 portion beyond said abutment which may be readily gripped to withdraw the pin. 70

2. A cotter-pin consisting of a single piece of wire substantially cylindrical in cross-section, including a body portion, an abutment or shoulder intermediate of the ends of the wire, and a head or grip portion beyond said abutment. 80

3. A cotter-pin consisting of a single piece of wire, including a straight body portion, a head or grip portion and a portion bent laterally from the general direction of the body intermediate of said body and head to form an abutment or shoulder limiting the extent to which the cotter-pin may be 90 inserted. 85

4. A cotter-pin consisting of a piece of wire substantially circular in cross section and having a body portion terminating at one end in a portion bendable laterally to 95 prevent the withdrawal of the pin, an abutment or shoulder at the opposite end to limit the extent to which the pin may be inserted, and a projection beyond said abutment adapted to be gripped to withdraw 100 the pin. 100

5. A cotter-pin consisting of a single piece of wire, having its terminal portions in alinement, and an intermediate portion bent laterally to form a shoulder or abutment. 105

Signed at New York, in the county of New York and State of New York, this 3d day of January, A. D. 1918.

PAUL E. KELECOM
